[57] CLAIM

The ornamental design for a combined cart and bowling
ball bag, as shown.

DESCRIPTION

FIG. 1 is a rear perspective view of the combined cart
and bowling ball bag showing my new design;
FIG. 2 is a rear elevational view thereof;
FIG. 3 is a front elevational view thereof;
FIG. 4 is a side elevational view thereof viewed from
the left side of FIG. 3;
FIG. 5 is a side elevational view thereof viewed from
the right side of FIG. 3;
FIG. 6 is a top view thereof; and
FIG. 7 is a bottom view thereof.

FIG. 1

FIG. 2
